UNITED STATES PATENT OFFICE

146,786

DESIGN FOR A GAME BOARD

Dewey W. Camp, Jackson, and Oscar B. Loper,
Hattiesburg, Miss.

Application December 10, 1945, Serial No. 124,570

Term of patent 3½ years

(Cl. D34—5)

To all whom it may concern:

Be it known that we, Dewey W. Camp and Oscar B. Loper, both citizens of the United States, residing at Jackson, in the county of Hinds and Hattiesburg, in the county of Forrest, respectively, State of Mississippi, have invented a new, original, and ornamental Design for a Game Board, of which the following is a specification, reference being had to the accompanying drawing, forming part thereof.

We claim:

The ornamental design for a game board, as shown.

DEWEY W. CAMP.
OSCAR B. LOPER.
